CLAIM

(57) The ornamental design for a pneumatic tire, as shown and described.

DESCRIPTION

FIG. 1 is a perspective view showing an ornamental design of a pneumatic tire of a disclosed embodiment with parts of the sidewall portions and bead portions being indicated by broken lines;

FIG. 2 is a front view of the ornamental design of the pneumatic tire shown in FIG. 1, with a top plan view and bottom plan view of the pneumatic tire appearing the same as the front view;

FIG. 3 is a rear view of the ornamental design of the pneumatic tire shown in FIG. 1;

FIG. 4 is a right side view of the ornamental design of the pneumatic tire shown in FIG. 1;

FIG. 5 is a left side view of the ornamental design of the pneumatic tire shown in FIG. 1; and,

FIG. 6 is partial front view of the ornamental design of the pneumatic tire shown in FIG. 1, showing an enlargement of the portion 6-6 in FIG. 2, with the tread pattern continuously repeating around the circumference of the tire.

The broken line showing of the sidewall, inner bead and the peripheral boundary between the tire tread and the sidewall is included for the purpose of illustrating environment and forms no part of the claimed design.
